UNITED STATES PATENT OFFICE.

JOSEPH A. BOYER AND HENRY E. BRYANT, OF JACKSONVILLE, FLORIDA.

TURPENTINE-DISTILLING APPARATUS.

1,312,826.

Specification of Letters Patent.

Patented Aug. 12, 1919.

Application filed February 9, 1918. Serial No. 216,275.

To all whom it may concern:

Be it known that we, JOSEPH A. BOYER and HENRY E. BRYANT, citizens of the United States, both residing at Jacksonville, 5 in the county of Duval and State of Florida, have invented certain new and useful Improvements in Turpentine-Distilling Apparatuses; and we do hereby declare that the following is a full, clear, and exact description of the invention, such as will enable others skilled in the art to which it appertains to make and use the same.

This invention relates to turpentine stills, and has particular reference to condensing apparatuses therefor.

The object of this invention is to provide an apparatus for separating the turpentine which has been condensed from the vaporous contingent which normally exists in the 20 still warm distillate, and condensing the vaporous contingent into rectified turpentine.

A further object of the invention is to provide a separator for removing the water 25 from the pure turpentine, and then cooling the latter to atmospheric temperature to condense it to its normal specific gravity for barreling.

A further object of the invention is to 30 make the process of condensing the vaporous contingent of the distillate a part of the water and turpentine separation process, so that the rectified turpentine which results from the condensation of the vaporous contingent will be automatically added into the 35 main body of the distillate to go through the separating process therewith.

It is a well known fact that the distillate which comes from the worm of the usual distilling apparatus possesses an appreciable 40 degree of heat, and that approximately one-tenth part of the spirits passes entirely through said worm in vaporous form and escapes into the atmosphere from the outlet 45 of the worm. Furthermore, the distillate consists of a mixture of turpentine and water which must be separated. Furthermore, the turpentine, in its heated state as it is received from the worm or condenser is so 50 hot that it is impossible to barrel it before a thorough cooling, without making the turpentine liable to payment for losses due to the shrinkage of the turpentine within the barrels as the product cools by condensation,

and assumes its normal specific gravity. 55 Generally speaking, then, it is the purpose of this invention to provide a condensing and separating apparatus which receives the normal distillate from a still and delivers all of it in the form of pure thoroughly 60 cooled and condensed turpentine which may be barreled and shipped.

With the above objects in view, and such others relating to the details of construction, as may hereinafter appear, our invention will now be fully set forth and described, reference being had to the accompanying drawings.

In the drawings:

Figure 1 is a vertical section through the 70 apparatus of the present invention,

Fig. 2 is a section on line 2—2 of Fig. 1,
Fig. 3 is a section on line 3—3 of Fig. 1,
Fig. 4 is a section on line 4—4 of Fig. 1,
Fig. 5 is a detail view,
Fig. 6 is a section on line 6—6 of Fig. 5,
Fig. 7 is a further detail view, and
Fig. 8 is a detail of a supporting bracket.

Referring more particularly to the drawings, 75 1 represents a tank which may have any exterior conformation, except that it must be comparatively high, and is subdivided on a line somewhat above the middle of its height by a transverse partition or floor 2. Upon the floor or partition 2 are transversely connected by means of the cross bars 4, said cross bars 4 providing supports for a plurality of coils or worms 5. The coils 5 are preferably three in number, 80 and are contained one within the other in spaced relation, and are furthermore built up of such a number of turns as will meet the requirements of the particular apparatus which is installed. The upper ends of the coils 5 terminate in a common manifold or coupling 6 from which water is fed into the coils. The lower ends of the coils 85 terminate in a similar manifold 7, from which the pipe 8 conducts the water through the wall of the tank for further use as will hereinafter appear.

The standards 3 and the cross bars 4 support the coils above the floor or partition 2 so as to provide a chamber 9 therebetween 95 within which the distillate from the distilling apparatus or the worm thereof is delivered through a pipe 10 which is entered

through the wall of the cylinder 1 above the partition 2. From the open end of the pipe 10, the distilled spirits fall upon an incline plate or baffle 11, which is preferably formed of glass, the arrangement being such that the fall from the end of the pipe on to the baffle is practically noiseless, so as not to disturb or destroy the usefulness of the ear trumpet 12 carried by the pipe 11 and which is employed in apparatuses employing secondary condensers whereby an expert operator may ascertain the contents and condition of the distilling spirits. Also, provision is thereby made for the periodical extraction of spirits from the end of the pipe 10 by the insertion of a cup into the chamber 9 through the inspection doorway or trap 13. Below the partition 2, the tank 1 is double walled, so that a comparatively heavy water space or chamber 14 is provided, and furthermore, parallel transverse walls 15 subdivide the lower part of the tank into a pair of chambers 16 and 17 and also form a water space 18 which communicates upon opposite sides with the water chamber 14, so that the chambers 16 and 17 are entirely surrounded by water jackets. The water chambers or spaces 14 and 18 are connected with a water supply by way of the pipe 8, above described, which is coupled into the wall 1 of the tank at a suitable point, a valve 19 in the pipe 8 providing a proper control element. A circulation is permitted through the chambers 14 and 18 by means of a draw-off valve 20 located near the upper end of the chamber walls, and a release valve 21 at the top thereof provides an escape for air which might be otherwise confined in the chambers by the rise of the water therein. When it becomes necessary to completely drain the water from the chambers, the valved outlet 22 at the bottom of the structure is employed.

The chambers 16 and 17 communicate with one another by means of an over-flow port 23 which is passed through the walls 15 so as to traverse the chamber 18, the port 23 being located at a height above the bottom of the tank which is determined by the capacity of the apparatus, as will hereinafter appear. The chamber 9 overflows into the chamber 16 through an over-flow device 24 which empties into a trough or spout 25, the latter passing to a point just above the bottom of the chamber 16. The over-flow device 24 also provides a trap which confines a certain quantity of liquid within the chamber 9 whose level acts as a seal against the passage of vapor from the chamber 9 through the over-flow device 24. Thus, the over-flow device or trap 24 consists of a flat and comparatively broad mouth 26 which lies flat against the partition 2, and empties at its rear end into a funnel 27 which terminates the upper end of the trough or spout 25. Between the mouth 26 and the funnel 27 the broad flat structure of the device is humped or upwardly curved in an elevation 28 which rises above the mouth 26 a distance equal to the vertical dimension of said mouth, so that the passage of liquid through the trap is only possible when the level in the chamber 9 exceeds in depth the height of the mouth 26. In this manner, any vapors which issue from the inlet pipe 10 are prevented from being drawn through the over-flow outlet from the chamber 9 into the chamber 16. When it is necessary to completely drain the chamber 9, a plug 29 which is entered into the partition 2 to cover a drainage port 30 whose upper end is flush with the upper surface of the partition 2, is removed, the plug being accessible through the door 13. The chamber 16 is drained through an outlet port 31 which is branched into a take-off conduit 34 which is controlled by means of a globe valve 35. The branch 34 is connected to a source of water supply by any convenient means so that as a preliminary step to the operation of the apparatus water may be introduced into the chamber 16 for such purposes as will hereinafter appear.

The chamber 17 has an outlet spout conduit 36 passing through the walls of the chamber 14 at a level slightly below the level of the over-flow port 23, the conduit 36 terminating, generally, in a filling spout from which barrels may be filled with the condensed turpentine, a suitable valve 37 providing for the control of the outlet. The chamber 17 receives the finally condensed and cooled turpentine as a commerical product, this body of spirits being received through the port 23 from the chamber 16 in which the turpentine is separated from the water of condensation which has come through the chamber 9 with the distillate from the condenser, this separation resulting gravitally by reason of the different specific gravities of the water and spirits. A gage 38 which is disposed upon the outside of the chamber 16 is properly arranged to indicate the relative level of spirits and water within the chamber 16.

In its operation, the utility of the present condensing and separating apparatus rests principally in the recovery of the usual one-tenth part of the turpentine spirits which has always passed off as a vaporous waste after the distillate has passed through the worm of the old distilling apparatus. Therefore, in installing the apparatus of this invention, the tank 1 is so disposed that the pipe or conduit 10 which is the usual spirit outlet from the distilling apparatus will deliver the product into the chamber 9.

the spirits falling upon the baffle or incline 11 in a noiseless manner so as not to destroy the effectiveness of the ear trumpet 12. As stated, the distillate, consists of one-tenth 5 vapor and therefore nine-tenths condensed spirits and water, still in a warm state. The condensed product passes from the chamber 9 through the trap 24 into the chamber 16, where, by the action of gravity the water 10 collects at the bottom of the chamber and the turpentine lies thereon in a superimposed body. If it is necessary for the proper operation of the apparatus, a body of water may be introduced into the bottom of the 15 chamber 16 through the water pipe 34 and the inlet 31, thus elevating the body of spirits which rest thereon to a level where it will overflow from the chamber 16 into the chamber 17 through the port 23. Vice 20 versa, if the water body becomes too great in the chamber 16, it may be drained by opening the valve 33 so that the water may be drawn off through the pipe 32. Within 25 the chamber 16, the condensed spirits undergo a cooling process through the action of the water in the chambers 14 and 18 which entirely surrounds the chamber 16.

The vapor which enters the chamber 9 and is separated from the condensed spirits rises 30 in the space around the coils 5, the latter having been filled with still or circulating water which is distributed from the manifold or coupling 6 into the several coils. The condensed products which result from the 35 circulation of the turpentine vapors among the coils 5 falls into the chamber 9 and is added to that body of distillate which overflows into the chamber 16.

As soon as the level of the turpentine in 40 the chamber 16 reaches the point where it will overflow through the port 23, it passes as a commercial product into the chamber 17, with the exception of the fact that it is still above its normal specific gravity because it 45 still contains a certain degree of heat. As it cools in the chamber 17, however, the water in the surrounding chambers 14 and 18 completely cool the distillate, so that by the time it reaches that point where it will 50 overflow through the outlet 36, it is condensed to its normal specific gravity, and is ready to be barreled immediately for shipment without danger of future adjustment for shrinkage of the contents of the barrel 55 by reason of the fact that the turpentine was barreled before it had thoroughly cooled. When the distilling process is over, and there still remains within the chamber 16 a body 60 of turpentine which cannot pass through the port 23 and by reason of the low level of the water body in said chamber 16, the latter may be increased by an additional water supply from the pipe 34, until the turpentine body has been raised to completely drain

into the chamber 17. After this, the turpentine then remaining in chamber 17 may be forced out of this chamber 17 through outlet conduit 36, by continuing inflow of water through 34 until sufficient has followed the turpentine into chamber 17 to raise all the 70 turpentine to the level of the outlet 36. Then the chambers 16 and 17 may be completely drained of water (which by reason of gravitational action will be their only contents,) by use of the outlets 31 and 39 respectively. 75

Also, when desired, the water jacket of the chambers may be drained in any suitable manner, as by the valve 40 to prevent damage from freezing or for other purposes. 80

From the foregoing description it will be apparent that we have devised a simple and effective condensing, separating and cooling apparatus by means of which practically a one hundred per cent. return may be secured 85 from the distilling process, first, because of the positive recovery of the usual one-tenth vaporous waste of turpentine and secondly because of the proper cooling and condensing of the turpentine to its normal specific 90 gravity before barreling for shipment. The apparatus is practically self-contained to carry out the three steps in a single receptacle or tank, and therefore embodies within the limits of required space and parts of an 95 old apparatus, the means effecting the complete recovery of turpentine spirits which has been described.

What we claim as our invention is:

1. In a turpentine distilling apparatus, a 100 chamber for receiving mixed vaporous and liquid distillate, a passage extending from said chamber, a vapor trap in said passage, and means associated with the chamber for condensing the vaporous distillate. 105

2. In a turpentine distilling apparatus, a chamber adapted to receive condensate and vapors of a distillate, a second chamber, a duct connecting the bottom of the first chamber with the second chamber, a vapor trap in 110 said duct and means associated with the first chamber for condensing vapor therein.

3. In a turpentine distilling apparatus, a chamber adapted to receive condensate and vapors of a distillate, a second chamber, a 115 duct connecting the bottom of the first chamber with the second chamber, a vapor trap in said duct, and cooling coils positioned in the first named chamber.

4. In a turpentine distilling apparatus, a 120 chamber, a second chamber mounted on the first chamber, a pipe depending from the bottom of the second chamber within the first chamber to a point adjacent the bottom of the first chamber, means for preventing the passage of vapor through said pipe and means associated with the second chamber for cooling vapor therein. 125

4

5. In a turpentine distilling apparatus, a chamber, a second chamber disposed above the first chamber, a pipe depending from the second chamber and a duct extended from 5 said pipe horizontally on the bottom of the second named chamber and having a portion thereof upwardly bowed to form a vapor trap and means associated with the second named chamber for condensing vapor 10 therein.

Copies of this patent may be obtained for five cents each, by addressing the "Commissioner of Patents, Washington, D. C."

In testimony whereof, we affix our signatures in the presence of witnesses.
